METHOD AND MACHINE FOR WINDING LINES, CORDS AND THE LIKE ON CARDS

Orrin MacMurray, Bloomfield, N. J., assignor to B. F. Gladding & Co. Inc., South Otselic, N. Y., a corporation of New York

Application October 27, 1933, Serial No. 695,465

19 Claims. (Cl. 242—50)

This invention has for its general object a machine for winding or coiling lines, cords, and the like on cards, and particularly on the face of the cards and securing the coils to the cards. The lines or cords may be fishing lines, or other lines or cords of either yarn or fiber material, or cords, as wire cords, such as are used for hanging pictures.

Another object of the invention is a machine for coiling the lines or cords on the face of the card and attaching the same to the card by tongues on the card, which tongues serve as studs around which the coil is wound and as a securing means by being looped over the wound coil and attached at their free ends to the card.

Another object of the invention is a machine for winding the coils on the tongues of the cards where the tongues are struck from the cards leaving slots, and looping the tongues over the wound coil and projecting them through the slots to interfit therewith and thereby fasten the coil on the card.

It further has for its object a winding machine including rotating heads between which the card is held and which have an opening and closing movement to insert the card and remove the same with the coil thereon, together with means for locating the card on one of the heads and with the tongues in juxtaposition to the tongue looping mechanism, which locating means is automatically shifted when the heads are closed to form a clearance for the line or cord passing from the skein or bobbin to between the rotating heads during the winding operation.

It further has for its object a mechanism for deflecting or positioning the tongues on the card so that they are in position to form studs on which the coil is wound and also in a position to be looped over the coil and secured at their free ends to the card at the end of the winding operation.

It further has for its object a tongue looping mechanism.

It further has for its object a method of winding or coiling lines, cords and the like on cards and securing them to the cards by means of tongues projecting from the face of the cards.

Other objects will appear throughout the specification.

The invention consists in the novel features and in the combinations and constructions herein-after set forth and claimed.

In describing this invention, reference is had to the accompanying drawings, in which like characters designate corresponding parts in all the views.

Figure 1 is a side elevation, partly broken away, of a winding machine embodying my invention.

Figure 2 is an enlarged fragmentary elevation of the rotating element which includes opposing heads.

Figures 3 and 4 are respectively face views of the opposing heads.

Figure 5 is a fragmentary central longitudinal sectional view through the opposing heads showing the same when brought together and in their position assumed, when the coil is being wound.

Figure 6 is a sectional view on line 6—6, Figure 5, looking to the left.

Figure 7 is a fragmentary sectional view of parts seen in Figure 5, showing the position of the parts during the tongue looping operation.

Figure 8 is a sectional view through the opposing heads, showing the position of the parts before the heads are finally clamped together and are in the intermediate position just prior to the withdrawal of the card locating means, the looping mechanism being omitted, this view being on the plane of line 8—8, Figure 4.

Heretofore in winding lines, cords and the like and applying them to cards, the coils have either been previously wound, as in the case of picture cords and then afterwards applied in coil form to the cards and secured thereto; or in winding other lines, as fishing lines, a card has been placed in the winding machine and the coil wound adjacent thereto and afterwards tied thereto by means of cords.

By my machine, the card is located between the winding heads, the coil wound thereon, on tongues or studs and when wound, the tongues or studs are folded over and the free ends secured to the card, all in one operation of the machine or working period, although the winding step and the tongue securing step are consecutive.

My method for winding lines, cords and the like on, and securing the same to, cards, consists in deflecting tongues provided on the cards from the plane of the card, effecting a relative winding movement of the card and the line or cord to coil the same on the tongues, which serve as studs, and finally looping the tongues over the wound coil and securing the free ends thereof to the card.

More specifically, the method consists in deflecting from the plane of the card, tongues struck from the card and arranged radially relatively to a center, effecting relative winding movement of the line or cord to coil the same on the tongues, which now serve as studs, and finally looping the tongues over the coil and extending them through the slots left in the card by the

tongues, by striking the tongues from the card, and hence binding the coil on the face of the card.

The cards on which the coils are wound and to which they are secured, are formed with a plurality of tongues extending radially relatively to the card with their inner ends joined to the card and preferably, the tongues are struck from the card, leaving radially extending slots complementary thereto with the tongues joined to the card at the inner ends of the slots, and after the coils are wound on the face of the cards about the base portions of the tongues, as studs, the free end portions of the tongues are looped outwardly over the coils and their free ends project 15 ed through the slots and interfitted therewith.

This card or form of package for coils, lines, cords etc., per se, forms no part of this invention, but forms the subject matter of my application Ser. No. 692,484, filed October 6, 1933.

20 The cards may be of any suitable contour, but are preferably square.

1 designate the card; 2 the tongues struck therefrom leaving complementary radially extending slots 3. When the cards are formed, the tongues lie close to the plane of the card. Preferably, there are four tongues and slots and the tongues and slots, as here shown, are in the fanciful form of a fish.

30 The machine for winding the lines, cords, etc. and securing them to the cards, includes a rotating element comprising a pair of opposing heads having relative axial movement, one toward and from the other, and means for effecting such movement, said element also having
35 means for supporting the card between the heads and means for preliminarily locating and supporting the card before the heads are brought together and further includes means for deflecting the tongues of the card out of the plane of
40 the card when the heads are shifted toward each other, so that the tongues may serve as studs on which the line is wound, and also means embodied in said element and operable to move the deflected tongues around the wound coil and se-
45 cure the ends thereof to the card.

11 designates the bed, or frame, of the machine supported by suitable legs 12.

13 and 14 designate respectively, the heads of the rotatable winding element of the machine, these heads being arranged in axial alignment and opposed to each other, and one of them, as the head 14, being shiftable axially toward and from the other head 13. The head 13 is carried by a suitable shaft 15 journaled in any suitable manner in bearings 16 and 17 mounted in standards 18 and 19 rising from the bed 11 of the machine. The shaft is rotated by suitable power mechanism including an actuator or pulley 20 loosely mounted on the shaft and connected thereto to drive the same through clutch sections 21 and 22 rotatable respectively with the actuator 20 and the shaft 15. The section 21 is shiftable into and out of engagement with the section 22, and as here illustrated, it is a unit with an actuator or pulley 20, and the pulley 20 is shiftable therewith. The pulley 20 and the clutch section 21 are shifted in any well known manner, as by a lever or treadle 23 pivoted at 24 between its ends to the bed of the machine, and having a fork 25 thrusting against the pulley to shift the same axially toward the clutch section 22. The lever 23 also has a brake arm 26 carrying a brake shoe 27 for coacting with the outer face of the clutch section 22 to stop the same and hence, stop the head 13 when the clutch is re-

leased. The movement of the pedal lever 23 is against the action of a returning spring 28. Hence, the operator holds the clutch engaged by means of the pedal lever 23 during a turning operation, and upon the removal of his foot from the pedal, the spring 28 reacts permitting the clutch section 21 to disengage from the clutch section 22, and the brake arm 26 to retard the momentum of the rotating heads 13 and 14.

The shaft 15 has built into or mounted therein 10 a case or box 29 mounted coaxially therewith and hence, balanced with respect to the same. This box is for the purpose of receiving cards on which the coils have been wound, as the coils are wound up in say dozen or two dozen lots, and the coils 15 on a number of cards connected in series. This box is here shown as rectangular, as the cards are usually rectangular and as having a hinged lid or cover 30 on one side thereof, and an opening 31 in its bottom. The lid, or cover, is held 20 closed by a spring or snap catch 32. The open bottom is for the purpose of facilitating the removal of a batch of cards from the box when the cover is open. The box is mounted concentrically 25 along a diameter thereof with the axis of the shaft 15 so that it extends on diametrically opposite sides of the axis of the shaft, and is balanced centrifugally during the rotation of the shaft 15.

centrally during the rotation of the shaft 13. The head 14 is mounted to shift axially with, but rotate relatively to a sliding shaft 33 mounted in 30 suitable guides 34, 35, at the upper ends of standards 36 rising from the bed of the machine, the head 14 being mounted coaxially with the head 13. The head 14 is shifted axially for the purpose of bringing the heads together after the 35 card has been located preliminary to winding, and for separating the heads to permit the removal of the card with the coil attached thereto, and for inserting a new card. For this purpose, the axially movable shaft 33 is provided with 40 means for manually shifting it axially, or sliding it axially in its bearings, here shown as a toggle including links 37 and 38 pivoted together at 39 by a stop, or a knuckle joint, and pivoted respectively at their outer ends at 40 to the axially 45 movable shaft 33, and at 41 to an adjustable rod 42 carried by the bearing 34 or standard 36. This rod 42 is here shown as threaded and provided with adjusting nuts 43 and 44 thereon adjustable to locate pivot 41 of the rod to conform to the thickness of the coils to be wound, it being understood that one lot of the coils may contain a greater length of lines, or cords than another lot, and hence, be thicker than others. One of the links, as the link 38 is provided with a suitable 50 handle 45 for opening and closing the toggle and hence, opening or closing the head 14 relatively to the head 13.

The rotating element consisting of the heads 13 and 14 is provided with means for initially supporting and locating the card before the head 14 is closed onto the head 13, or on the card held by the head 13, and as here shown, this supporting and locating means is carried by the head 13. 60

As here illustrated, and as seen in Figures 4 and 8, this card locating means includes a plurality of fingers 51 carried at the outer ends of levers 52 located in recesses or slots 53 formed in the head 13, the levers and slots extending inwardly in a general direction toward the center of the head 13, and these levers are actuated to project the fingers 51 beyond the face of the head 13 by springs 54 acting upon levers 55 pivoted at 56 in the recesses 53, the levers being articulated by pin-and-slot connections at 57 to the inner 75

ends of the levers 52. The levers 53 also have arms 58 which extend or project out beyond the face of the head 13 into the path of the head 14, so that when the head 14 is finally closed on the 5 card 1, the levers 55 will be actuated to actuate the levers 52 to withdraw the fingers 51 out of the space between the heads, thus leaving a clearance for the portion of the line or cord passing from a reel, bobbin, or a skein to have clearance 10 space during the winding of the coil.

As seen in Figure 4, two of the sets of levers 52 and 55 are arranged on opposite sides of a radius of the head 13, and another pair are arranged on opposite sides of the same radius, but in alignment, and all of these levers 52 and 55 are located on one side of another diameter at a right angle to said radius, that is, a horizontal diameter when the parts are in the position shown in Figure 4. This arrangement of the levers leaves the space 20 above the horizontal diameter entirely open for the insertion and removal of a card when the machine is stopped, and it is intended that the machine be stopped with the heads 13, 14, in the position shown in Figures 3 and 4, or in the position shown in Figure 2. The card used, in the 25 illustrated embodiment of my invention, is as shown in Figure 4 mounted with one corner portion between the two fingers 51^a and with two fingers 51^b supporting two other corners. The head 14 is formed with notches 60 for receiving the ends of the fingers 51.

The rotating head 14 is provided with a suitable hub 61 on the face thereof, having a curved or beveled periphery 62, this forming a seat on 35 which to wind the coil between the tongues 2 of the card which serve as studs. When the head 14 is clamped toward the head 13, the end of the hub presses the card 1 against the face of the head 13, as seen in Figure 7, but just prior to the 40 time that the hub comes in full clamping engagement with the head 13, the center portion of the card engages the arms of the levers 53, as shown in Figure 8, to move the fingers 51 out of the plane of the card. This clamping operation is performed by straightening the toggle consisting of 45 the links 37 and 38. When the machine is open, the springs 54 react to bring the fingers 51 back into position to support the card so that it is supported until removed by the operator and 50 placed in the box 29.

The hub 61 is interchangeable with other hubs of a different capacity. That is, hubs that are thicker or thinner, for the purpose of winding thicker or thinner coils. The hubs are detachably secured to the head 13 in any suitable manner, as by screws 63, Figure 5.

When the cards 1 are preliminarily supported on the fingers 51, the tongues 2 thereof are lying in, or near, the plane of the card, and means is 60 provided for deflecting the tongues out of the plane of the card into position where they serve as studs on which the coil is wound, as seen in Figure 5.

As here illustrated, the head 13 is provided 65 with a plurality of shoulders provided at the ends of the pins 71 spaced apart around the axis of the head 13, and located in position to engage the inner or base portions of the tongues 2 when the card is supported, as shown in Figures 4 and 70 8, on the fingers 51. The hubs 61 are provided with notches 72 for receiving the deflected tongues, and also the ends of the pins 71, and these pins and notches serve also to transmit the drive of the head 13 to the head 14 during the 75 winding operation. The ends of the pins 71 and

the bottoms of the notches are complementally shaped or beveled to deflect the base portions of the tongues with enough angularity so that they serve as studs to receive the coil.

The means for looping the tongues 2 over the coil after it is wound about the tongues 2, the hub 62, and the projecting ends of the pins 71, and securing the free ends of the tongues to the card, or interfitting them in the slots 3, comprises fingers 81 spaced apart about the center 10 of the head 14, there being one finger for each tongue and the common operating member for the fingers shiftable axially of the head 14 to project the fingers beyond the face of the head 14, and bend the tongues around the coil and 15 work them through the slots 3 to the toggle. The head 13 is provided with suitable recesses 82 located beneath the slots for receiving the projecting ends of the fingers 81 and also permitting the tongues to be forced through the slots in 20 the card to the rear of the card in order to interlock with the slots. As here illustrated, these fingers are carried by a sleeve or cap 83 25 slideable on a hub 84 on the outer side of the head 14, against the action of a light returning spring 85 encircling the hub 84 and extending at one end into an annular recess 86 in the head 13 and thrusting against the bottom thereof, and thrusting at its other end against the end of the sleeve or cap 83, as seen in Figure 5. The 30 sleeve or cap 83 is secured against displacement and limited in its sliding movement by a key or pin 83^a extending through a lengthwise slot 84^a in the sleeve and threading into the hub 84. The hub 84 of the head 13 is rotatably mounted on a cylindrical axial extension 88 of the non-rotatable shaft 33 which is here shown as square, this extension 88 having a thrust collar 89 for the hub 84. The hub 84 is secured to the extension by a pin 88^a through the hub 84 and projecting into an annular groove 88^b in the extension 88. The head 14 is also provided with recesses 90 for the deflected tongues 2, as seen in 35 Figure 5, and through which recesses the fingers 81 pass during the looping operation of the tongues 2, the recesses 90 being aligned with the recesses 82. The heads 13, 14 are provided with suitable gages as lines 101, 102 to align them in the event they should get out of juxtaposition or alignment.

The line or cord being wound, is drawn from a bobbin or a skein on a reel, and passes through an indicator which shows when a predetermined length of line, or cord, has been wound, all of which devices are old and form no part of this invention.

In operation, the end of the line, after being passed through the indicator, passes through a suitable notch 95 in the head 13 and then clamped between the cover 30 and the box 19. A card is then placed in the machine against the face of the head 13, the card being then supported by the fingers 51, as shown in Figure 4. As the cards are square, and as the slots 3 and tongues 2 extend diagonally relatively to the center thereof, and as there are four tongues and slots, or the tongues and slots are spaced equal distance apart, it requires no attention on the part of the operator to properly locate or mount the cards on the fingers 51 in order to locate the tongues and slots in juxtaposition to the deflecting pins 71, and the looping fingers 81. The head 14 is then closed by straightening the toggle links 38, 39 by means of the handle 44 thus moving the head 75

14 first into the position shown in Figure 8, and then into the final position shown in Figure 5 wherein the tongues are deflected out of the plane of the card into the notches 72 of the hub 61 with their upper ends in the recesses 90 of the head 14. The operator then depresses the pedal lever 23 engaging the clutch sections 21, 22, whereupon the heads 13, 14, rotate and the line, or cord, is wound about the hub 61 over the bases of the tongues 2, and on the ends of the pins 71, as seen in Figure 5. When a predetermined amount of line has been wound, as shown by the indicator before referred to, the operator releases his foot from the pedal lever 23, thus disengaging the clutch section 21 from the clutch section 22 and applying the brake from the clutch section 22 and stopping the heads 13 and 14 from rotation, and if they do not stop in the proper position, that is, in the position shown in Figures 3 and 4, the operator can readily turn the heads by hand so that they are in this position, and when in this position the cover side of the box 29 is up. The operator then shifts the sleeve 83 axially of the hub 84 causing the fingers 81 to loop the tongues from the position shown in Figure 5 to that shown in Figure 7. The operator then opens the head 14 by opening the toggle links 38, 37, into the position shown in Figure 1, whereupon the card can be readily lifted off from the fingers 57 and deposited in the box 29. The length of line, or cord, running from the skein to the coil is then looped through the slot 95, a new card inserted, the machine closed as before, and the operation repeated, the cover on the box closing on this length of cord anchoring it for the winding of the next coil. This operation is repeated until the required number of coils wound in series have been completed, when the cards with the coils thereon are removed from the box and another lot started.

This machine is particularly advantageous in that it effects a great saving of time in winding the coils and attaching them to the cards, and particularly in winding and attaching to cards compared with methods used wherein the coils are first wound and then affixed to the cards, or the coils wound on the cards and affixed thereto by additional tying cords. Although I have shown and described a machine for applying coils to square cards, it is obvious that it may be used for applying cords to other shaped cards, and that also modifications may be made in the mechanism here shown and described without departing from the spirit of my invention.

What I claim is:

1. The method of winding lines, cords and the like on cards having tongues extending radially from a center, consisting in deflecting the tongues from the plane of the card effecting relative winding movement of the card and the line or cord to coil the same on the tongues, which serve as studs, and finally looping the tongues over the wound coil and securing the outer ends thereof to the card.

2. The method of winding lines, cords, and the like on cards consisting in deflecting from the plane of the card, tongues struck from the card and arranged radially relatively to a center, effecting relative winding movement of the card and the line or cord to wind the same on the tongues, which serve as studs, and finally looping the tongues over the wound coil and extending them through the slots left in the card by

the tongues when the tongues are formed from the card.

3. In a machine for winding lines, cords and the like on cards having tongues on the face thereof extending radially relatively to a center, said machine including a rotating element having means for supporting the card coaxially therewith, means for deflecting the tongues outward from the plane of the card to provide studs on which the line or cord is wound and means operable to loop the tongues over the coil thereon and secure the ends of the tongues to the card. 10

4. In a machine for winding lines, cords and the like on cards having tongues extending radially outwardly relatively to a center, said machine including a rotating element including a pair of opposing heads having relative axial movement, one toward and from the other, and means for effecting such movement, said element having means for holding the card between the heads and means for deflecting the tongues out of the plane of the card when the heads are shifted toward each other, whereby the tongues serve as studs on which the line or cord is wound, and means carried by said element operable to 25 loop the deflected tongues around the wound coil and secure the ends thereof to the card. 25

5. In a machine for winding lines, cords and the like on cards having tongues extending radially outwardly relatively to a center, said machine including a rotating element including a pair of opposing heads having relative axial movement, one toward and from the other, and means for effecting such movement, said element having means for supporting the card between the heads and means for deflecting the tongues out of the plane of the card when the heads are shifted toward each other, whereby the tongues serve as studs on which the line or cord is wound, said deflecting means comprising studs spaced apart on the face of one of said heads around the axis thereof, one stud for each tongue, an axial hub on the other head formed with notches for receiving the deflected tongues and means on the head provided with the hub and shiftable axially thereof operable to loop the deflected tongues over the wound coil and secure the tongues to the card. 35

6. In a machine for winding lines, cords and the like on cards having tongues on the face thereof extending radially relatively to a center, said machine including a rotating element including opposed axially aligned heads and means for rotating said element, said heads having relative axial movement, one toward and from the other, said element having means for supporting the card between the heads with the tongues deflected out of the plane of the card, means on one of the heads operable to loop the tongues around the coil wound on the tongues and secure the ends thereof to the card. 55

7. In a machine for winding lines, cords and the like on cards having tongues on the face thereof extending radially relatively to a center, said machine including a rotating element including opposed axially aligned heads and means for rotating said element, said heads having relative axial movement, one toward and from the other, said element having means for supporting the card between the heads with the tongues deflected out of the plane of the card, means on one of the heads operable to loop the deflected tongues around the coil wound on the tongues and secure the ends thereof to the card, said 70

- means including fingers carried by one of the heads and movable axially thereof, one finger for each tongue, an operating member operable to shift the fingers to loop the tongues over the coil, 5 after the heads are together and the coil wound, and means for withdrawing the fingers out of the path of the deflected tongues.
8. In a machine for winding lines, cords and the like on cards having tongues on the face thereof extending radially relatively to a center, 10 said machine including a rotating element including opposed axially alined heads and means for rotating said element, said heads having relative axial movement, one toward and from the other, said element having means for supporting the card between the heads with the tongues deflected out of the plane of the card, means on one of the heads for looping the deflected tongues around the coil wound on the tongues and securing 15 the ends thereof to the card, said means including fingers carried by one of the heads and movable axially thereof, one finger for each tongue, an operating member operable to shift the fingers to loop the tongues over the coil after 20 the heads are together and the coil wound, and spring means for withdrawing the fingers out of the path of the deflected tongues.
9. In a machine for winding lines, cords and the like, on cards having slots arranged radially 25 relatively to a center and tongues complementary to the slots and extending radially outwardly from the inner ends of the slots, said machine including a rotating element having means for supporting the card coaxially therewith, means 30 for deflecting the tongues outward from the plane of the card to provide studs on which the line or cord is wound, and means operable to loop the tongues around the coil thereon and project the ends thereof through the slots.
10. In a machine for winding lines, cords and the like on cards having slots arranged radially 35 relatively to a center and tongues complementary to the slots and extending radially outwardly from the inner ends of the slots, said machine including a rotating element including a pair of opposing heads having relative axial movement, one toward and from the other, and means for effecting such movement, one of the heads having 40 means on its face opposed to the other for supporting the card, and said element having means for deflecting the tongues out of the plane of the card when the heads are shifted toward each other, whereby the tongues serve as studs on which the line or cord is wound, and means on the other 45 head operable to loop the tongues around the wound coil and project the ends thereof through the slots of the card.
11. In a machine for winding lines, cords and the like on cards having slots arranged radially 50 relatively to a center and tongues complementary to the slots and extending radially outwardly from the inner ends of the slots, said machine including a rotating element including opposing axially alined heads and means for rotating said 55 element, said heads having relative axial shifting movement, one toward and from the other, one of the heads having means for supporting the card and said heads having means cooperating to deflect tongues out of the plane of the card upon 60 relative shifting movement of the heads to bring the heads toward each other, said deflecting means comprising spaced apart studs on the face of one of the heads around the axis thereof, one stud for each tongue, and an axial hub on the other head formed with notches for receiving the deflected tongues, and means on the head provided with the hub and shiftable axially thereof for looping the tongues around the wound coil 65 and projecting the ends thereof through the slots, the last-named means including a plurality of fingers spaced apart around the axis of said element and shiftable in a direction axially of the heads and alined respectively with the tongues, 70 and an operating member common to all of said fingers and shiftable axially of the head in which the fingers are mounted, the other head being formed with recesses alined with the slots in the card and with said fingers.
14. In a machine for winding lines, cords and the like on cards having slots arranged radially 75 relatively to a center and tongues complementary to the slots and extending radially outwardly from the inner ends of the slots, said machine including a rotatable element including opposing heads having axial shifting movement, one toward and from the other, one head being formed with a plurality of studs spaced apart around its axis, one stud for each tongue and arranged to

- deflect the tongues out of the plane of the card upon relative axial movement of the heads toward each other and the other head being formed with a hub on its face opposed to the former head, said 5 hub having notches for receiving the deflected tongues and said studs and a plurality of fingers carried by the head provided with the hub, the fingers being alined with the tongues respectively and movable in a direction axially of said element, 10 means for operating the fingers including a member common to all of them and carried by the head which supports the fingers and being shiftable axially thereof, the card supporting head having recesses alined with the slots in the card and said 15 fingers.
15. In a machine for winding lines, cords and the like on cards, said machine comprising opposing rotating heads having relative axial shifting movement to bring the heads together and 20 to separate them, one of the heads being provided with means for supporting the card, mechanism for rotating the card supporting head, and means for deflecting the tongues of the card out of the plane of the card, when the heads are 25 brought together and for transferring the rotation of the card supporting head to the other head.
16. In a machine for winding lines, cords and the like on cards, said machine comprising a rotating element for supporting the card during 30 the winding operation, a box for receiving a plurality of cards with coils attached thereto including a case rotatable with said element and mounted coaxially therewith.
- 35 17. In a machine for winding lines, cords and the like on cards, said machine comprising a rotatable element for supporting the card during the winding operation, a box for receiving a plurality of cards with coils attached thereto including a case rotatable with said element and mounted coaxially therewith, said box being provided with

a cover on one side thereof having means for gripping the line or cord when the cover is closed to anchor the line or cord during the winding operation of a line or cord on another card.

18. In a machine for winding lines, cords and the like on cards, said machine including a rotating element including opposed axially alined heads, and means for rotating said element, said heads having relative axial closing and separating movement, one toward and from the other, said 5 heads having means for holding the card when the heads are together, and one of the heads having means for supporting and locating the cards when the heads are separated, said supporting and locating means being shiftable into and out 10 of the space between the heads, means for normally pressing them into the space between the heads in position to support the card, and means operable by the closing of the heads together for 15 moving the locating and supporting means out 20 of the space between the heads.

19. In a machine for winding lines, cords and the like on cards, said machine including a rotating element including opposed axially alined heads, and means for rotating said element, said 25 heads having a relative axial closing and separating movement, one toward and from the other, said heads having means for holding the card when the heads are together, and one of the heads having means for supporting and locating the 30 cards when the heads are separated, said supporting and locating means including fingers for engaging the edge of the card, shiftable into and out of the space between the heads when separated, parts projecting into said space behind the 35 card in position to be depressed by the other through the interposed card when the heads are closed and motion transmitting and reversing means between said parts and the fingers.
